RAILWAY TRAFFIC CONTROLLING
APPARATUS

Charles J. Kelloway, Wilmington, N. C.

Application April 21, 1932, Serial No. 606,589

15 Claims. (Cl. 246—41)

My invention relates to railway traffic controlling apparatus, and particularly to apparatus for signaling systems of the type commonly installed on single track railways.

5 One feature of my invention consists in an improved and novel means for approach lighting the signal lamps of the wayside signals, the apparatus and circuits being so arranged as to light the lamp of only the signal which a particular 10 train is approaching, and to prevent the lighting of the lamps of opposing signals, signals to the rear of a train and other signals not required for governing the immediate movement of the 15 train. In signal systems of the type herein involved it is customary to rely upon primary batteries located along the trackway as the source of energy for controlling the operation of the signals and for lighting the signal lamps. By my invention a great saving of the current output 20 from these batteries, which must be renewed from time to time, is accomplished, resulting thereby in a material reduction in the cost of maintenance.

The directional control for the lighting of 25 the signal lamps is accomplished in my invention without additional apparatus other than that required for other approach lighting schemes. Other features of my invention will appear as the specification progresses.

30 I will describe one form of apparatus embodying my invention, and will then point out the novel features thereof in claims.

In the accompanying drawings, Figs. 1a and 35 1b when placed together with Fig. 1a at the left constitute a diagrammatic view of one form of apparatus embodying my invention when applied to the wayside signals for a stretch of single track railway. Fig. 2 is a series of diagrams showing the signals which are lighted for typical train 40 movements on a stretch of single track railway to which my invention has been applied. In the following description, reference will be made to these figures in which like reference characters designate similar parts. In order to simplify the 45 drawings certain circuit controlling contacts in Figs. 1a and 1b are located at points not adjacent to the relays controlling the contacts. In each such instance the reference character corresponding to the governing relay is placed just 50 above the contact and the contact is shown in a position corresponding to the normal condition of the relay. For example, the front contact 21 in Fig. 1a is governed by the track relay 3TR and this contact is shown closed inasmuch as the relay is normally energized.

55 Referring to Figs. 1a and 1b, the traffic rails 10 and 10a of a stretch of single track railway extending between two passing sidings PS and PS1 are divided by means of the customary insulated rail joints into a plurality of track sections 5 1T, 3T, 4T, 5T, 6T, 7T and 8T. The track section at the left-hand end of Fig. 1a and the track section at the right-hand end of Fig. 1b are each designated by the reference character 7T, and so if Fig. 1a be placed at the right of Fig. 10 1b there will be formed a complete siding location, and at certain places in the following description this arrangement of Figs. 1a and 1b will be assumed. Each track section is provided with a customary track circuit consisting of a source 15 of current such as a battery 11, and a track relay designated by the reference character TR plus a numeral corresponding to the associated section.

Traffic through this stretch of railway is gov- 20 erned by two sets of signals, of which signals 1, 3, 5, and 7 govern traffic moving from the left to the right, and signals 2, 4, 6, and 8 govern traffic from the right to the left. In this de- 25 scription I will speak of trains moving from the left to the right as eastbound trains, and those moving from the right to the left as westbound trains. These signals may be of any suitable type, and as here shown are searchlight signals, such as described and claimed in the United 30 States Letters Patent, No. 1,864,224, granted June 21, 1932, to W. B. Wells for Light signals. For the purpose of this application, it is deemed sufficient to but briefly describe these signals. Re- 35 ferring to signal 4, for example, it includes a rotor 12 biased by a permanent magnet (not shown) and operated by an operating winding 13. The energizing of the operating winding 13 with current of one polarity causes the rotor 12 to be rotated in one direction moving the 40 signal to the clear indication position. Energizing the operating winding 13 with current of the reverse polarity causes the rotor 12 to be rotated in the opposite direction to move the signal to the caution indication position, while when the 45 operating winding 13 is deenergized, the rotor 12 is automatically returned to a center position which is the stop indication position. Associated with the rotor 12 is a signal lamp 19. As pointed out in detail in the aforementioned application, 50 when the rotor 12 is rotated to the clear position, a green colored filter is moved in front of the lamp 19 and a green signal light is displayed when lamp 19 is lighted. When the rotor 12 is rotated to the caution indication position, a yellow col- 55

ored filter is moved in front of the lamp 19 so that with lamp 19 lighted a yellow signal light is displayed. In like manner the positioning of the rotor 12 in the center position moves a red colored filter in front of the lamp 19 and a red signal light is displayed whenever the lamp 19 is energized. The rotor 12 actuates a set of circuit controlling contacts in such a manner that the contact 14-15 is closed only in the clear position, the contact 14-16 closed only in the caution position, and the contact 17-18 closed both in the stop and caution positions. To assist in understanding the operation of these contacts, the reference characters G, Y, and R are placed at the contacts indicating that the contacts are closed in the clear, caution and stop positions, respectively. Each of the wayside signals functions in a manner similar to that described for signal 4. The head block signals 1 and 8 are each provided with a second signal lamp 20 to form a fixed signal. This extra signal lamp 20 is connected in parallel with the normal signal lamp as will appear later and always displays a red light when the lamp is energized.

The source of energy for operating each signal and the relays associated therewith, and also for lighting the signal lamp is a battery of proper voltage located at the signal. In the drawings, this battery is not shown, its two terminals being indicated by the reference characters B and N with a numeral prefixed corresponding to the associated signal. For example, the reference character 4B designates the positive terminal of the battery associated with signal 4, and the reference character 4N designates the negative terminal of the same battery.

Associated with each signal is a slow-release control relay and a slow pick-up thermo relay, designated by the reference characters HP and TH, respectively. A numeral is prefixed to each reference character HP and TH to designate the associated signal. Again referring to signal 4, the relay 4HP is normally energized by virtue of a stick circuit extending from the battery terminal 4B, through contact 14-15, its own front contact 22, and winding of relay 4HP to the opposite battery terminal 4N. When the signal 4 occupies the caution position, this circuit includes the contacts 14-16 and 17-18 as will be readily understood by an inspection of Fig. 1a. When the signal occupies the stop position, both contacts 14-15 and 14-16 are open and the relay 4HP is deenergized. In the event the relay 4HP is deenergized, due to the signal 4 having been set at the stop position, and the signal is then moved to either its caution or clear position, a circuit extends from the terminal 4B, through contact 14-15 or contacts 14-16 and 17-18 as the case may be, back contact 22, and heating element 23 of thermo relay 4TH to the negative battery terminal 4N. After an interval of time, the heating of the element 23 closes the contact 24 to complete the pick-up circuit for the relay 4HP, and once energized that relay is retained energized by its stick circuit above traced, and the circuit to the heating element 23 is opened at the back contact 22. It follows that relay 4HP will not be immediately picked up after signal 4 is moved to its caution or clear position, but its pick-up will be delayed until the thermo relay 4TH has had time to close its contact 24. At the entrance signals 2 and 1, the relay HP and the thermo relay TH are replaced by a single relay designated by the reference character DP which is controlled by a simple circuit easily traced.

Each HP and DP relay acts as a pole-changing relay governing the operating circuit for the signal in the rear, as will shortly appear.

The intermediate signals 4, 3, 5, and 6 and the head block signals 1 and 8 are each provided with the usual directional stick relay which is here designated by the reference character S plus a numeral corresponding to the signal. Referring to the stick relay 3S associated with the signal 3, its pick-up circuit can be traced from the battery terminal 4B along wire 25, back contact 26 of the opposing stick relay 4S, back contact 27 of the opposing control relay 4HP when that relay is deenergized, wire 31, back contact 28 of the track relay 3TR, front contact 29 of the control relay 3HP, and winding of relay 3S to the battery terminal 4N. Once relay 3S is picked up, a stick circuit is closed at its own front contact 30 as will be readily understood by an inspection of Fig. 1a. It follows that when an eastbound train passes the location of signal 3, when that signal indicates either caution or clear, and shunts the track relay 3TR, the directional stick relay 3S is picked up during the release period of the control relay 3HP after the track relay 3TR is shunted, and once picked up relay 3S is retained energized by its stick circuit until both relays 3TR and 3HP are reenergized.

The relay 3HP and the stick relay 3S control the circuit for the operating winding 13 of signal 1 in the rear. When relay 3HP is energized, this circuit can be traced from the battery terminal 3B, through front contact 31 of relay 3HP, winding of a relay 3ER to be shortly described, front contact 32 of the track relay 4TR, line wire 1H, front contact 33 of track relay 1TR, winding 13, common line wire 1C, and front contact 34 of relay 3HP to the battery terminal 3N. With relay 3HP deenergized and the directional relay 3S picked up, this circuit extends from the terminal 3B through front contact 35 of relay 3S, back contact 34 of relay 3HP, line wire 1C, winding 13, front contact 33, line wire 1H, front contact 32, winding of relay 3ER and back contact 31 of relay 3HP to the battery terminal 3N. With relays 3HP and 3S both deenergized, the circuit to the operating winding 13 of signal 1 is open. It follows that with the control relay 3HP picked up, current of one polarity is supplied to the operating winding 13 of signal 1 to operate that signal to its clear position. When relay 3HP is deenergized but the directional stick relay picked up, current of the reverse polarity is supplied to the winding 13 of signal 1 to move that signal to its caution position. When relays 3HP and 3S are both deenergized, the winding 13 of signal 1 is without energy. That is to say, the signal 1 will be cleared when signal 3 in advance is at stop by the energizing of the directional relay 2S, thereby permitting following train movements in the usual manner for single track signal systems, but signal 1 will be held in the stop position for opposing train movements. It is to be noted that the circuit for the winding 13 of signal 1 is also governed by track relays 1TR and 4TR of the track sections 1T and 4T, respectively.

The approach lighting relay 3ER is associated with the signal 3 and as its winding is included in series with the above traced operating circuit for the signal 1 in the rear, it will be energized whenever this operating circuit is closed. In a similar manner each signal is provided with an approach lighting relay designated by the reference character ER plus a numeral correspond-

ing to the associated signal. The circuit for the signal lamp 36 of signal 3 can be traced from the battery terminal 4B along wire 25, back contact 26 of the directional stick relay 4S for the 5 opposite intermediate signal 4, back contact 27 of the control relay 4HP associated with the opposite signal 4, wires 37 and 38, resistance 39, back contact 40 of the approach lighting relay 3ER, and lamp 36 to the battery terminal 4N. 10 Thus the lighting of lamp 36 not only requires the deenergizing of the usual approach lighting relay 3ER, but it further requires that the opposing directional relay 4S and the opposing control relay 4HP both be deenergized. It is to be 15 noted that this second requirement, namely, the deenergizing of the opposing directional relay and the opposing control relay, for completing the circuit for the lamp 36 of signal 3, is obtained by connecting the circuit to the energizing circuit 20 for the associated directional relay at the back contact of the opposing control relay. To be explicit, the circuit for lamp 36 is connected by wire 38 to the wire 37 of the energizing circuit of relay 3S from which point it extends to 25 the back contact 27 of the control relay 4HP, and thence through back contact 26 of relay 4S to positive battery terminal 4B. The circuit for the lamp 19 for the opposite intermediate signal 4 is similar to that just described for the 30 lamp 36 of signal 3. This circuit for lamp 19 is from battery terminal 3B, through back contact 35 of the opposing directional relay 3S, back contact 41 of the opposing control relay 3HP, wires 42 and 43, resistance 44, back contact 45 of the associated approach lighting relay 4ER, and lamp 19 to the battery terminal 3N. The 35 circuit for the lamp of each intermediate signal of my system will be similar to that described above for each lamp of the opposite intermediate 40 signals 3 and 4.

An eastbound train moving away from siding PS toward siding PS1 will shunt the track relay 1TR as it enters the section 1T and that relay will be released. With the track relay 1TR released and its front contact 46, which is included in the operating circuit for winding 13 of the signal 4, opened, the signal 4 will move to its stop position and the associated relay 4HP will in turn be deenergized. Upon the release of 45 the relay 4HP the circuit including the pole-changing contacts of relay 4HP, the approach lighting relay 4ER of signal 4, and the operating winding of the signal 6 is without current and the relay 4ER will be deenergized and the 50 signal 6 will be set at the stop position. Upon the signal 6 moving to its stop position, the relay 6HP will be deenergized and, upon the release of relay 6HP, the circuit including its pole-changing contacts, the approach lighting relay 55 6ER for the signal 6, and the operating winding of the signal 8 is without current and the relay 6ER will be deenergized and the signal 8 will be set at its stop position. Consequently, all 60 the opposing west-bound signals up to the siding PS1 will assume the stop position and their respective approach lighting relays will be deenergized in response to the eastbound train entering the section 1T. The lamps of these westbound signals will, however, remain dark 65 70 since each lamp circuit includes a back contact of the HP relay for the opposite eastbound signal, for example, the circuit for lamp 19 of the signal 4 includes the back contact 41 of the relay 3HP.

75 The release of the track relay 1TR and the opening of its front contact 33 in response to the train entering the section 1T will remove current from the circuit including the operating winding 13 of the signal 4 and the approach lighting relay 3ER of the signal 3. Thus, the eastbound signal 4 behind the train will be set at stop and the approach lighting relay 3ER for the first eastbound signal in advance of the train will be released. This circuit for the winding of signal 4 and relay 3ER will also be held open at the front contact 32 of the track relay 4TR during the time the train occupies the section 4T. Since the directional relay 4S is normally down and its back contact 26 is closed, the release of the relay 3ER and the closing of its back contact 40, together with the release of the relay 4HP and the closing of its back contact 27 in response to the signal 4 moving to the stop position, will be effective to complete the circuit for the lamp 36 of signal 3 and that lamp will be lighted to display to the eastbound train as it travels through sections 1T and 4T, a green, yellow or red light according to the position of the signal 3. When the train passes the signal 3 at its clear or caution position and shunts the track 20 relay 3TR of section 3T, the signal 3 will be set at its stop position, the relay 3HP will be deenergized and the directional relay 3S will be picked up and its stick circuit closed during the release period of the relay 3HP in the usual 25 manner for such systems. The circuit for the lamp 19 of the signal 4, which was previously held open at the back contact 41 of relay 3HP, will now be open at the back contact 35 of the relay 3S so that the opposing westbound signal 35 4 will still be dark. The shunting of the track relay 3TR and the opening of its front contact 49 not only removed current from the winding 13 of the signal 3 but also deenergized the approach lighting relay 5ER of signal 5 since that relay is 40 included in the same circuit as winding 13 of signal 3. The directional relay 6S being normally down, and since relay 6HP was released in response to the signal 6 moving to its stop position, the release of the approach lighting relay 45 5ER in response to the train shunting track relay 3TR will be effective to complete the circuit for the lamp of signal 5 and that lamp will be lighted to display the signal 5 to the eastbound train in sections 3T and 6T. As soon as the rear end 50 of the train has vacated the sections 1T and 4T and the relays 1TR and 4TR are picked up and their respective contacts 33 and 32 are closed, the operating circuit for signal 1 will be completed and the relay 3ER included in that circuit 55 will be reenergized with the result that its back contact 40 will be opened and the lamp 36 of signal 3, the eastbound signal immediately in the rear of the train, will become dark. However, if a following train should now enter section 1T 60 and shunt the track relay 1TR, the relay 3ER will be again deenergized and the lamp 36 will be lighted to display the signal 3 to this following train. When the first eastbound train passes signal 5 and shunts the track relay 5TR, the signal 5 will be set at stop, the directional relay 5S will be picked up and the approach lighting relay 7ER for the next eastbound signal 7 will be deenergized to light its lamp, the operation being similar to that described when the train passed 65 signal 3 and entered the section 3T. Again, as soon as the rear of the eastbound train vacates the section 6T, the lamp of the signal 5 will become dark in the same way the lamp 36 became dark as the train passed out of the section 4T 70 75

and it is thought unnecessary to repeat the description. Furthermore, the energizing of the directional relay 5S when the eastbound train passes signal 5 will hold open the circuit for the lamp of the opposing westbound signal 6 in the same manner the circuit for the lamp 19 of signal 4 was held open when the train entered section 3T and the directional relay 3S was picked up.

When the rear of the train vacates the section 6T, the operating circuit for the winding 13 of signal 3 will be completed at the front contact 49 of the relay 6TR, with the result that the signal 3 will move to its caution position, the relay 3HP will be reenergized and the directional relay 3S will become deenergized. The circuit for the lamp 19 of signal 4, the second westbound signal to the rear of the train, will now be open at the back contact 41 of the relay 3HP whereas it was open at the back contact 35 of the relay 3S, and consequently that lamp will continue to be dark. It is clear, therefore, that for an eastbound train the lamp of each eastbound signal will be lighted as the train approaches the signal, will become dark as soon as the rear of the train passes the signal, will be relighted for any following train, and the lamps of all opposing westbound signals will remain dark. The operation of the system for a westbound train moving from siding PS1 toward siding PS will be similar. This time the lamp of each westbound signal will be lighted as the train approaches the signal and will become dark as soon as the rear of the train passes, and the lamps of all eastbound signals will remain dark.

Referring to the entrance signal 2, its signal lamp 50 is provided with a circuit that includes the back contact 51 of the associated approach lighting relay 2ER, back contact 52 of the control relay 1HP associated with the oppositely located head block signal 1, and the back contact 53 of the directional relay 1S for signal 1, and so is similar to the lamp circuits described for the intermediate signals 3 and 4. In addition, the lamp circuit for the entrance signal 2 is provided with a branch path around the back contact 53 of the directional relay 1S which path includes a back contact 54 of the track relay 1TR. When an eastbound train approaches the signal 2, the lamp 50 remains dark due to its circuit being held open at the back contacts 51 and 52 of the relays 2ER and 1HP, respectively. When a westbound train approaches the signal 2, its lamp circuit is closed as soon as the train enters the track section 4T deenergizing the approach lighting relay 2ER to close its back contact 51, inasmuch as the control relay 1HP was deenergized when the signal 1 was set at stop as this westbound train passed the head block signal 8 at the next siding to the east. As the westbound train passes the signal 2 and travels away from that signal, the lamp 50 becomes dark due to its circuit being opened at the back contact 51 of the approach lighting relay 2ER which is now energized. The branch path which includes the back contact 54 of track relay 1TR is effective to light the signal lamp 50 of signal 2 in the event a train should back out of the siding PS past the signal 1 causing its directional relay 1S to become energized in the usual manner. Thus signal 2 will display a light to this train should it wish to proceed west from the track section 4T. It is to be noted that if the train passes on to the east out of the section 4T, the lamp 50 becomes dark as soon as the train vacates the section 4T and track relay 1TR picks

up, as the directional relay 1S is now up holding open its back contact 53.

Assuming Fig. 1a to be placed at the right of Fig. 1b so as to form a complete siding layout, the lamp circuit for the head block signal 1 includes the back contact 55 of the approach lighting relay 1ER only. Thus this signal will be displayed for an approaching eastbound train as soon as it enters the section 4T opening the front contact 58 of the track relay 1TR. As the operating circuit for the entrance signal 1 at the west end of the siding also includes the front contact 57 of the track relay 1TR, the approach lighting relay 1ER for the signal 1 will remain deenergized while the eastbound train occupies the section 4T. A westbound train approaching the head block signal 1 will also open this operating circuit for the signal 1 as soon as it enters the section 4T and thus both signal lamps 20 and 59 for the head block signal 1 will be lighted 20 while a train occupies the sections 4T and 1T. The lamp circuits for the lamps of the head block signal 8 are similar to those for the head block signal 1.

In Fig. 2 is a series of diagrams showing which signals are lighted during train movements over an extended stretch of single track railway. It is believed these diagrams are self-explanatory and need no further description. It is to be noted, however, that a signal is displayed only 30 as a train approaches the signal travelling in the direction in which the signal governs traffic, except that the lamps for the head block signals are lighted whenever the track section adjacent to the passing siding and the section immediately 35 in advance of the signal are occupied.

Although I have herein shown and described only one form of apparatus embodying my invention, it is understood that various changes and modifications may be made therein within 40 the scope of the appended claims without departing from the spirit and scope of my invention.

Having thus described my invention, what I claim is:

1. In combination, a stretch of railway over which traffic normally moves in each direction, two signals located along the stretch to govern traffic in opposite directions through the stretch and each comprising a movable member and a lamp cooperating therewith to give a plurality of indications, approach circuit means one for each signal operative to light the lamp of the associated signal in response to a train occupying the stretch in the rear of the signal, a directional relay for each signal energized in response to a train passing its signal travelling in the direction governed by said signal, and means governed by the directional relay of each signal effective to prevent the lighting of the opposing signal when said relay is energized.

2. In combination, a stretch of railway over which traffic normally moves in each direction, two signals located along said stretch to govern traffic in opposite directions and each comprising a movable member and a lamp cooperating therewith to give a plurality of indications, a normally energized control relay associated with each signal and governed by traffic conditions in advance of its signal, and lighting circuits, one for each signal each of which circuits includes a back contact of the control relay associated with the opposing signal.

3. In combination, a stretch of railway over which traffic normally moves in each direction,

- two signals located along the stretch to govern traffic in opposite directions, a circuit controlling device for each signal and governed by the position of its signal, a directional relay for each signal responsive to a train passing its signal traveling in the direction governed by said signal, and lighting circuits, one for each signal each of which circuits is controlled jointly by the circuit controlling device and the directional relay associated with the opposing signal. 5
4. In combination, a stretch of railway over which traffic normally moves in each direction, two signals located along said stretch to govern traffic in opposite directions, a normally energized control relay associated with each signal and governed by traffic conditions in advance of its signal, a normally deenergized directional relay for each signal, an energizing circuit for 10 each directional relay each of which includes a back contact of the opposing control relay and a back contact of the opposing directional relay, and lighting circuits, one for each signal each of which circuits includes the same back contacts of 15 the opposing control and directional relays that are included in the energizing circuit of the associated directional relay. 15
5. In combination, a stretch of railway over which traffic normally moves in each direction, two signals located along the stretch to govern traffic in opposite directions, a normally energized control relay associated with each signal and governed by traffic conditions in advance of its signal, a normally deenergized directional 20 relay for each signal energized in response to a train passing its signal traveling in the direction governed by said signal, and lighting circuits, one for each signal each of which circuits includes a back contact of the control relay and a back contact of the directional relay associated with the opposing signal. 25
6. In combination, a stretch of railway over which traffic normally moves in each direction, an eastbound signal and a westbound signal for said stretch each comprising a movable member and a lamp cooperating therewith to give a plurality of indications, a lighting circuit for each signal adapted when closed to light its signal lamp, approach circuit means one for each signal to close the lighting circuit of the associated signal in response to a train occupying the stretch in the rear of the signal, a directional 30 relay for each direction of traffic energized in response to a train passing through the stretch travelling in the corresponding direction, and means governed by a directional relay effective to hold open the lighting circuit for the opposing signal when said relay is energized. 35
7. In combination, a stretch of railway over which traffic normally moves in each direction, two signals located along said stretch to govern traffic in opposite directions, a directional relay for each signal, a lighting circuit for each signal normally operative to light the signal in response to a train occupying the stretch in the rear of the signal and which circuit includes a back contact of the directional relay associated with the opposing signal, and means for energizing a directional relay in response to a train travelling in the direction governed by its signal and thereby prevent the lighting of the signal governing traffic in the opposite direction. 40
8. In combination, a stretch of railway over which traffic normally moves in each direction, two signals located along said stretch to govern traffic in opposite directions, a directional relay for each signal, an energizing circuit for each directional relay each of which includes a back contact of the opposing directional relay, and lighting circuits, one for each signal each of which circuits includes the same back contact of 45 the opposing directional relay that is included in the energizing circuit of the associated directional relay. 50
9. In combination, a stretch of railway over which traffic normally moves in each direction, two signals located along said stretch to govern traffic in opposite directions, a normally energized control relay associated with each signal and governed by traffic conditions in advance of its signal, a normally deenergized directional 55 relay for each signal, an energizing circuit for 10 each directional relay each of which includes a back contact of the opposing control relay and a back contact of the opposing directional relay, and lighting circuits, one for each signal each of which circuits includes the same back contacts of 15 the opposing control and directional relays that are included in the energizing circuit of the associated directional relay. 15
10. In combination, a stretch of railway over which traffic normally moves in each direction, two signals located along the stretch to govern traffic in opposite directions, a normally energized control relay associated with each signal and governed by traffic conditions in advance of its signal, a normally deenergized directional 20 relay for each signal energized in response to a train passing its signal traveling in the direction governed by said signal, a normally energized approach lighting relay for each signal governed by traffic conditions to the rear of its signal; and 25 lighting circuits, one for each signal each of which circuits includes a back contact of its approach lighting relay, a back contact of the opposing control relay and a back contact of the opposing directional relay in series. 30
11. In combination, two successive track sections, two signals located at the junction of said track sections and set to govern traffic in opposite directions, a directional relay for each signal adapted to be energized in response to a train 35 entering the track section in advance of its signal when travelling in the direction governed by said signal, a lighting circuit for each signal closed in response to a train occupying the track section to the rear of its signal, and means controlled by 40 a directional relay effective when said relay is energized to hold open the lighting circuit for the opposing signal and thereby light a signal while a train occupies the track section to the rear of the signal only when said train is travelling to- 45 wards said signal. 50
12. In combination, two successive track sections, a signal located at the junction of said track sections and set to govern traffic in a given direction, an approach lighting circuit for the 55 signal adapted to be closed in response to a train occupying the track section to the rear of said signal, a directional relay energized in response to a train passing from the section in advance of the signal to the section to the rear of said signal 60 when travelling in a direction opposite that governed by said signal, and means controlled by the directional relay effective when said relay is energized to open the lighting circuit and thereby prevent the lighting of said signal while a train 65 occupies the track section to the rear of the signal when travelling away from said signal. 70
13. In combination, two successive track sections, a signal located at the junction of said sections to govern traffic in a given direction, a normally energized approach lighting relay adapted 75 to be deenergized in response to a train occupying the track section to the rear of said signal, a normally energized control relay adapted to be deenergized at times in response to traffic con- 75

ditions to the rear of said signal, a normally de-
energized directional relay adapted to be ener-
gized in response to a train passing from the sec-
tion in advance of the signal to the section to the
5 rear of said signal when travelling in a direction
opposite that governed by the signal; and a light-
ing circuit for the signal including a back con-
tact of the approach lighting relay, a back con-
tact of the control relay and a back contact of
10 the directional relay in series to thereby light
said signal only as a train occupies the track
section to the rear of the signal when travelling
towards the signal and to prevent the lighting of
the signal when a train travelling in either direc-
15 tion occupies the track section in advance of the
signal.

14. In combination, a railway signal set to gov-
ern traffic in a given direction, two successive
20 track sections to the rear of said signal, a track
relay for each section, a normally energized ap-
proach lighting relay for said signal arranged to
be deenergized when either of said track sections
is occupied, a normally deenergized directional
relay adapted to be energized in response to a

train travelling through the said track sections
away from said signal, a lighting circuit for said
signal including a back contact of the approach
lighting relay and a back contact of the direc-
tional relay in series, and a shunt path around
5 the said back contact of the directional relay
which includes a back contact of the track relay
for the section next in the rear of said signal.

15. In combination, a stretch of single track
railway, a first set of signals to govern traffic in 10
one direction through the stretch, a second set
of signals to govern traffic in the opposite direc-
tion through the stretch, an approach lighting
means for each signal adapted to close a lighting
circuit for its signal in response to a train occu- 15
pying the stretch to the rear of its signal, direc-
tional means associated with each direction of
travel arranged to hold open the lighting circuit
of each signal of the opposing set of signals ir-
respective of the approach lighting means in re- 20
sponse to a train traversing said stretch in the
associated direction.

CHARLES J. KELLOWAY.
